UNITED STATES PATENT OFFICE.

EDWIN C. BLOMBERG, OF ROCKFORD, ILLINOIS, ASSIGNOR OF ONE-HALF TO FRANK OLANDER, OF ROCKFORD, ILLINOIS.

DRAWER-GUIDE.

No. 867,102.

Specification of Letters Patent.

Patented Sept. 24, 1907.

Original application filed July 16, 1906, Serial No. 326,341. Divided and this application filed April 8, 1907, Serial No. 367,116.

To all whom it may concern:

Be it known that I, EDWIN C. BLOMBERG, a citizen of the United States, residing at Rockford, in the county of Winnebago and State of Illinois, have invented new and useful Improvements in Drawer-Guides, of which the following is a specification.

The object of this invention is to construct a simple and efficient guide for drawers used in the make up of articles of furniture.

10 In the accompanying drawings. Figure 1 is a horizontal section through an article of furniture and the lower portion of a drawer showing the arrangement of the guides. Fig. 2 is an isometrical representation of the underside of a drawer to which are attached a 15 guide and a roller, and in this view two guides and two rollers are shown in the position they occupy but detached from the case.

The case or article of furniture 1 and the drawer 2 are of the ordinary construction, and to which my 20 improvements are applied. To the underside of the bottom 3 of the drawer is permanently secured a guide 4 and a roller 5. To the case 1 are permanently secured two guides 6 and 7 and two rollers 8 and 9.

The roller 5 rests in contact with the two guides 6 25 and 7 alternately, that is, the roller should be of a slightly less diameter than the distance between the guides in order that only one guide will be engaged at a time, and the two rollers 8 and 9 rest in contact with opposite edges of the guide 4. In pulling out

the drawer, the guide 4 and roller 5 move with it. 30 The roller 5 will roll in contact with the guides 6 and 7 alternately thereby directing the movement of the inner end or back edge of the drawer. The guide 4 will rotate the rollers 6 and 7, thereby directing the movement of the outer or front edge of the drawer. 35 These guides and rollers serve to hold the sides of the drawer free of the case, thereby preventing binding of the parts.

These improvements are especially adapted for long narrow drawers in which they are located in the 40 lengthwise center of the drawer.

I claim as my invention.

An article of furniture comprising a case and a drawer, means for guiding the drawer comprising two guides secured to the case and located in the direction of the movement of the drawer, two rollers secured to the case, one for each guide which is located at the outer end thereof, a guide secured to the bottom of the drawer and located parallel with the guides secured to the case, and a roller secured to the bottom of the drawer and located at the 50 inner end of the guides secured to the drawer, the roller secured to the drawer movable in contact with the guides secured to the case, and the guide secured to the drawer movable in contact with the rollers secured to the case, the rollers supported on vertical pivots. 55

In testimony whereof I have hereunto set my hand in presence of two subscribing witnesses.

EDWIN C. BLOMBERG.
